232,320

YARN SPLICER OR SIMILAR ARTICLE

D. Wayne Bledsoe, 1928 Dug Gap Road, Dalton, Ga.
30720, and R. Alton Cadenhead, P.O. Box 810, Fitzgerald, Ga. 31750

Filed Aug. 2, 1972, Ser. No. 277,419

Term of patent 14 years

U.S. Cl. D47—5   Int. Cl. D15—08

FIG 1

FIG 2

FIG 3

FIG 4

FIG 7

FIG 5

FIG 6

F I G 8

FIG. 1 is a front perspective view of a yarn splicer showing our new design;

FIG. 2 is a top plan view thereof;

FIG. 3 is a front elevational view thereof;

FIG. 4 is an end view as seen from the left of FIG. 3;

FIG. 5 is an end view as seen from the right of FIG. 3;

FIG. 6 is a perspective view thereof, in opened position;

FIG. 7 is a bottom plan view on a reduced scale; and

FIG. 8 is a rear elevational view thereof.

We claim:

The ornamental design for a yarn splicer or similar article, substantially as shown and described.
